Primary Examiner—Charles A. Rademaker(74) *Attorney, Agent, or Firm*—Jonathan Spangler**CLAIM**

The ornamental design for an intervertebral implant, as shown and described.

DESCRIPTION

FIG. 1 is a top perspective view of an intervertebral implant showing our new design;

FIG. 2 is a bottom perspective view thereof;

FIG. 3 is a side elevation view thereof; and,

FIG. 4 is a side elevation of the side opposite that shown in FIG. 3.
